UNITED STATES PATENT OFFICE.

MILLARD GILMORE, OF OAK PARK, ILLINOIS.

DOOR.

Application filed December 31, 1921. Serial No. 526,106.

To all whom it may concern:

Be it known that I, MILLARD GILMORE, a citizen of the United States, residing at Oak Park, in the county of Cook and State 5 of Illinois, have invented a new and useful Improvement in Doors, of which the following is a specification.

This invention relates particularly to the construction of fire-doors; and the primary 10 object is to provide a door of exceedingly staunch construction, of improved appearance, and capable of being manufactured very economically.

The invention is illustrated, in its preferred embodiment, in the accompanying drawings, in which—

Fig. 1 represents a fragmentary view of a building wall which is provided with a door-opening and which is equipped with the improved door; Fig. 2, an enlarged broken horizontal sectional view taken as indicated at line 2 of Fig. 1; Fig. 3, an enlarged broken vertical sectional view taken as indicated at line 3 of Fig. 1; Fig. 4, an elevational view of the reverse side of the door shown in Fig. 1; Fig. 5, an enlarged broken sectional view; and Fig. 6, a broken vertical sectional view of the marginal binding member of the door showing the construction of 25 one of the corners.

In the construction illustrated, A represents a wall which is provided with a door-opening A'; and B, the improved door.

In the illustration given, the wall is shown 35 equipped above the door-opening with a track 1; and the door is equipped with hangers 2 provided with rollers 3 which engage said track. Also, the wall is shown equipped with stops 4 for engaging the rear 40 vertical edge of the door, and with a stop 5 for engaging the front vertical edge portion of the door, these stops being adapted to hold the door close to the wall when the door is in a closed position.

The door B comprises vertical plates 6 which form one side of the door; transverse or horizontal plates 7 which form the other side of the door; interposed asbestos sheets 8; and a marginal binding member 9 which 50 has inwardly extending flanges secured to said plates.

In the illustration given, the door is shown as having three of the vertical plates 6 which are united together by lines of rivets 6^a.

55 Also, in the illustration given, three of the cross-plates 7 are employed, these cross-

plates being joined together by means of horizontal rows of rivets 7^a. All of the rivets preferably extend thru the door at the junctions of the vertical and horizontal corrugations, so that the side walls of the door are thus riveted together thru the intervening asbestos 8.

Each of the vertical plates 6 is provided with outwardly struck vertical panels 6^b which are joined together by relatively narrow, inwardly struck corrugations 6^c, which may be termed base-corrugations. Similarly, each of the cross-plates 7 is provided with outwardly struck horizontal panels 7^b which 70 are connected by inwardly struck, relatively narrow corrugations 7^c.

The marginal binding member 9 of the door is of the box form clearly shown in Fig. 3. It preferably is made by bending 75 a piece of sheet-metal into hollow form of rectangular cross-section and extending the margins of the sheet-metal inwardly from the hollow body of the marginal member. The inturned flanges 9^a of the marginal 80 member 9 are connected by rivets 10 with the sheet-metal plates 6 and 7 and the interposed asbestos sheets 8.

The box-form panel, by preference the marginal binding member 9, is provided by 85 first forming a tubular member of rectangular cross-section, but provided with the projecting flanges on one side, such member being of great enough length to form the entire binding member of the door; then 90 mitering the member at the proper points and bending it into the form of a rectangle conforming to the shape and size of the door. Thus, the marginal member is provided with the mitered edges 9^b which may 95 be joined together in any suitable manner, as by welding. Where the ends of the marginal member come together, as illustrated in Fig. 6, an angle-form connecting member 11 is employed to connect the extremities, the member 11 being secured to the hollow body by means of screw-bolts 11^a. If desired, the connecting member 11 and the bolts 11^a may be employed for 100 strengthening each of the corners of the marginal member, in lieu of the welding operation above referred to.

The construction described is exceedingly 110 staunch and durable, is capable of being manufactured more cheaply than the better types of construction now in use, and provides large air spaces between the plates

of the door. The improved door is also one of very greatly improved appearance. Preferably, the flanges 9^a of the marginal member 9 are located closer the front surface 9^c than they are to the rear surface 9^d of the marginal member; and the marginal member is projected rearwardly beyond the panels of the cross-plates 7, as clearly appears from Fig. 3. Thus, the marginal member 10 is adapted to bear against the wall completely around the door-opening when the door is in closed position. At the same time, the raised panels of the vertical plates 6, which are at the front side of the door, 15 are preferably substantially flush with the front surfaces 9^c of the marginal member. The result is that the front surface of the door presents an exceedingly pleasing appearance, giving a paneled effect. If the door be viewed in an oblique direction, the front surface has the appearance of being practically continuous, but with the pleasing paneled effect already noted.

As appears from Fig. 2, the marginal member 9 is provided at the front edge portion of the door with a perforation 12 which is adapted to receive the hook 5^a of the stop or binding member 5.

The improved construction is comparatively cheap, exceedingly strong and durable, and presents a pleasing appearance which has hitherto not been obtainable in fire-doors.

The improved binding member employed 35 on the door may be formed by suitable rolling operations, followed by mitering and bending, as above described. In connection with the improved binding member, any suitable corrugated plates may be employed, 40 but it is preferred to employ corrugated plates of the form shown. Where the door is small, a single vertical plate may suffice. Where the door is of larger dimensions, any suitable number of plates may be used.

The foregoing detailed description has 45 been given for clearness of understanding only, and no unnecessary limitations should

be understood therefrom, but the appended claims should be construed as broadly as permissible, in view of the prior art.

What I regard as new, and desire to secure by Letters Patent, is—

1. A door comprising corrugated plates extending cross-wise with respect to each other, and a marginal binding-member comprising an integral hollow sheet-metal body of substantially rectangular cross-section which is flangeless at its outer sides and which has projecting flanges at its inner periphery, said binding-member being mitered and bent to the form of the door and said flanges being interposed between and riveted to said plates. 55

2. A door comprising a sheet-metal box-form binding member of integral cross-section and having its margins affording flanges which extend inwardly from the inner peripheral wall of the binding-member, corrugated plates which extend cross-wise with respect to each other and whose margins embrace said flanges and have the end-edges of their corrugations abutting against the inner peripheral wall of said binding-member, rivets securing said plates to said flanges, and rivets connecting said plates at 70 points of intersection of the corrugations. 70

3. A door comprising vertical sheet-metal plates provided with vertical raised box-panels and intervening relatively narrow base-corrugations, horizontal sheet-metal 50 cross plates provided with horizontal raised box-panels and intervening narrow base-corrugations, rivets connecting said base-corrugations at intersecting points, and a sheet-metal marginal box-form binding-member of integral cross-section having its margins affording flanges which project inwardly from the inner periphery of the binding-member and are interposed between and riveted to said plates, the end edges of 85 said box-panels abutting against the inner peripheral wall of said binding-member. 90

MILLARD GILMORE.
